Charles Walter Ball

BY

Norman H. Ball
ATTORNEYS

UNITED STATES PATENT OFFICE.

CHARLES WILBUR BALL, OF RICHMOND HILL, NEW YORK.

RADIO ATTACHMENT FOR TALKING MACHINES.

Application filed May 12, 1922. Serial No. 560,416.

To all whom it may concern:

Be it known that I, CHARLES WILBUR BALL, a citizen of the United States, and resident of Richmond Hill, Long Island, 5 New York, have invented a new and useful Improvement in Radio Attachments for Talking Machines, of which the following is a specification.

This invention relates to an attachment 10 for talking machines, with the object in view of providing a device which may be connected with the horn of a talking machine and arranged to receive a set of head phones of a radio receiving instrument, 15 whereby the sound received by the head phones may be amplified and directed through the horn of the talking machine.

Another object is to provide a device 20 which will clarify the sound received by the lead phones and eliminate foreign and harsh noises.

Another object is to provide a device 25 which is simple, durable and inexpensive to manufacture.

Another object is to provide certain improvements in the form, construction and arrangement of the parts, whereby the above named and other objects may be effectively attained.

A practical embodiment of my invention 30 is represented in the accompanying drawing, in which—

Fig. 1 represents a plan view of a talking machine having the sound box and tone arm removed, and my improved device applied thereto.

Fig. 2 represents a side elevation of the 35 same, partly in section.

Fig. 3 represents a plan view of my device 40 on an enlarged scale.

Fig. 4 represents an end elevation of the same.

Fig. 5 represents a vertical section taken 45 in the plane of the line V—V of Fig. 4, and

Fig. 6 represents a vertical section taken in the plane of the line VI—VI of Fig. 5.

The device is of T-shaped construction, the vertical hollow member being denoted 50 by 2 and the horizontal branches by 3, 4. The horizontal branches are each provided with a passage 5, 6, respectively, which passages increase in diameter as they approach each other.

The vertical member has a passage 7 55 which connects at the junction of the pas-

sages 5, 6, and progressively increases in diameter to a point 8, where the walls of the member 2 are arranged parallel to the outlet 9. This outlet 9 is fashioned to fit 60 into the upturned recess 10 of the horn 11 which is secured in position in the cabinet 12 of the talking machine. The member 2 is also provided with a shoulder 13 which bears upon the walls surrounding the recess 10.

The free ends of the branches 3, 4, are provided with oppositely disposed cup-shaped elements 14, 15, each of which has a peripheral wall undercut to receive and 70 maintain a pad 16 of felt or other suitable material. Each of the pads 16 has a centrally arranged hole 17 which registers with the mouth of its passage in the branches 3, 4.

A head phone 18 having a pair of sound receivers 19, 20, connected by springs 21, is arranged to be engaged with the device so that the receivers 19, 20, will contact with the pads 16 in the oppositely disposed cup-shaped elements 14, 15, which receivers are yieldingly held in position by the springs 21. The head phone 18 and its adjacent mechanism is of well-known and approved construction, and I do not deem it necessary 80 to describe its specific mechanism since it is not claimed herein.

It is obvious that various changes may be resorted to in the form, construction and arrangement of the several parts without departing from the spirit and scope of my invention; hence, I do not intend to be limited to the specific details herein described, except as they may be included in the claims.

What I claim is:

1. A device of the character described comprising, a tubular member having its free end constructed for connection with an amplifying horn, and hollow branches having their free ends constructed to hold the two receivers of a radio head set, the passages in the branches increasing in diameter as they approach each other and the passage in the tubular member increasing in diameter from its junction with the branch passages.

2. A device of the character described comprising, a tubular member having its free end constructed for connection with an amplifying horn, and hollow branches provided at their free ends with members con-

structed to hold the two receivers of a radio comprising, a tubular member having its head set, and resilient pads located in said free end constructed for connection with an 20 branch members, the passages in the branches increasing in diameter as they approach each other and the passage in the tubular member increasing in diameter from its junction with the branch passages.

3. A device of the character described comprising, a tubular member having its 10 free end constructed for connection with an amplifying horn, and hollow branches provided with cup-shaped members at their free ends constructed to hold the two receivers of a radio head set, said cup-shaped members having undercut peripheral walls for 25 receiving and retaining resilient pads, and said resilient pads, the passages in the branches increasing in diameter as they approach each other and the passage in the tubular member increasing in diameter from 30 its junction with the branch passages.

In testimony that I claim the foregoing as my invention I have signed my name this 15 day of May, 1922.

4. A device of the character described

CHARLES WILBUR BALL.
